UNITED STATES PATENT OFFICE.

GEORGE S. BROWN AND LEWIS M. CARPENTER, OF JEWETT CITY, CONNECTICUT,
ASSIGNORS OF ONE-THIRD TO GROSVENOR ELY, OF NORWICH, CONNECTICUT.

RECEPTACLE FOR TRANSPORTING YARN, ROVINGS, OR THE LIKE.

Application filed May 17, 1922. Serial No. 561,768.

To all whom it may concern:

Be it known that we, GEORGE S. BROWN and LEWIS M. CARPENTER, citizens of the United States, and residents of Jewett City, 5 in the county of New London and State of Connecticut, have invented a new and useful Improvement in Receptacles for Transporting Yarn, Rovings, or the like, of which the following is a specification.

10 Box trucks commonly employed for transporting yarn, rovings or the like material are provided with flat tight bottoms on which collects foreign matter of all sorts, with which the material comes in contact

15 when the trucks are used for storage or transportation, thereby causing considerable damage to the material.

One object of our invention is to provide a portable receptacle for yarn, rovings or the like, having its bottom so shaped that it 20 will automatically clear itself through one or more openings in the bottom, of foreign matter.

In the conditioning of the material above 25 specified, it is common to provide a special conditioning or humidifying room into and out of which the material is conveyed before being taken to the loom.

Another object of our invention is to provide 30 a portable receptacle provided with means for humidifying the material as it is being transported, thus eliminating the special conditioning room and thereby obtaining a considerable saving in time and 35 expense in the handling of the material.

It has been common in washing out the box trucks commonly employed, to tip the trucks over sufficiently so that they may be washed by a hose.

40 Another object of our invention is to provide a portable receptacle of the character above specified which may be readily washed while in its normal upright position, the humidifying means being employed for this 45 purpose, if so desired.

Practical embodiments of our invention are represented in the accompanying drawings, in which

Fig. 1 represents in top plan one form of 50 our improved portable receptacle.

Fig. 2 represents an end view of the same.
Fig. 3 represents a side view.

Fig. 4 represents a cross section taken in the plane of the line IV—IV of Fig. 3, looking in the direction of the arrows. 55

Fig. 5 represents on an enlarged scale the valve connection for regulating the supply and the humidifying agent.

Fig. 6 represents a transverse vertical section through a second form of portable receptacle. 60

Fig. 7 represents a longitudinal vertical section through a third form of portable receptacle.

Fig. 8 represents a longitudinal vertical 65 section through a fourth form of portable receptacle.

In the form of portable receptacles shown in Figs. 1 to 4 inclusive, the uprising side and end walls are denoted by 1, 2 and 3, 4. 70 The bottom is shown as comprising four sections 5, 6 and 7, 8 sloping downwardly and inwardly. Along the lowermost portion of the bottom we provide an elongated slot 9. The hub of the bottom sections is 75 such that foreign matter which would tend to lodge on a flat bottom will be directed by gravity downwardly and outwardly through the elongated slot 9, thus making the receptacle self-cleaning. 80

This receptacle may be provided with suitable traction wheels 10, 11, and 12, 13 for ease in transporting the receptacle from place to place. Perforated passages are provided around the top and bottom of the receptacle 85 for directing the humidifying agent into the receptacle. In the present instance a perforated pipe 14 encircles the top of the receptacle and a perforated pipe 15 encircles the bottom of the receptacle, the two pipes 90 being connected by a vertical pipe 16 in which is located a two-way valve 17, arranged to open the inlet 18 either to the top encircling pipe or the bottom encircling pipe or to both, as may be desired. A humidifying agent supply source, not shown herein, may be removably connected to the inlet 18 of the valve through the pipe 19. If the humidifying agent is hot water, it would 95 preferably be introduced into the receptacle 100

through the top encircling pipe 14. If the humidifying agent is steam, it would preferably be introduced into the receptacle through the bottom encircling pipe 15. Furthermore, the valve 17 may be used for directing the humidifying agent, used either to the top or the bottom or to both the top and bottom of the receptacle.

It will also be seen that this humidifying agent may be utilized for washing out the receptacle when no material is located therein, without changing the receptacle from its normal vertical position.

By introducing the humidifying agent into the material while in the portable receptacle it will be seen that the use of a special conditioning or humidifying room is obviated as the material may be humidified as it is being transported to the loom, for instance. This will also save excess handling of the yarn. It will be understood that all excess moisture will drain away through the bottom of the receptacle and this will assist in carrying away all foreign matter.

It will also be seen that the self cleaning feature of the receptacle can be used without the humidifying feature, if so desired, hence we do not wish to limit ourselves to a portable truck with the humidifying feature attached thereto.

In Fig. 6 we have shown a portable receptacle in which the discharge opening or elongated slot 20 is located along one side of the receptacle, the entire bottom 21 being sloped laterally down to said slot. In Fig. 7 we have shown the discharge opening or slot 22 located along one end of the receptacle and the bottom 23 inclined longitudinally down to said slot. In Fig. 8 we have shown two discharge openings or slots 24, 25, with the sections 26, 27 of the bottom sloped downwardly toward the slot 24 and the sections 28, 29 of the bottoms sloped downwardly toward the slot 25. These are only a few of many different forms which our self cleaning feature may take, it being understood that one or more discharge openings may be employed and that the bottom of the receptacle is so shaped that no part of it lies in a horizontal plane, but that all parts are sloped at such an angle that loose material will slide towards the opening or openings by gravity, to cause the material to drop out of the receptacle through said opening or openings.

It is evident that various changes may be resorted to in the construction, form and arrangement of the several parts without departing from the spirit and scope of our invention; hence we do not wish to be limited to the particular embodiments herein shown and described, but

What we claim is:—

1. A portable receptacle for transporting

yarn, rovings or the like, and means carried thereby for humidifying the material while in the receptacle.

2. A portable receptacle for transporting yarn, rovings or the like, and means carried thereby for humidifying the material while in the receptacle, said means being fitted for removable attachment to the humidifying agent supply source.

3. A portable receptacle for transporting yarn, rovings or the like, said receptacle having perforated passages for directing a humidifying agent into the receptacle, and means for removably connecting said passages to the humidifying agent supply source.

4. A portable receptacle for transporting yarn, rovings or the like, said receptacle having perforated passages around its top and bottom for directing a humidifying agent into the receptacle, and means for removably connecting said passages to the humidifying agent supply source.

5. A portable receptacle for transporting yarn, rovings or the like, said receptacle having one or more openings through its bottom, the bottom being shaped to discharge foreign matter through said opening or openings, said receptacle having perforated passages for directing a humidifying agent into the receptacle, said humidifying agent serving also as an agent for washing out the receptacle.

6. A portable receptacle for transporting yarn, rovings or the like, said receptacle having one or more openings through its bottom, the bottom being shaped to discharge foreign matter through said opening or openings, said receptacle having perforated passages for directing a humidifying agent into the receptacle, said humidifying agent serving also as an agent for washing out the receptacle, and means for removably connecting said passages to the humidifying agent supply source.

7. A portable receptacle for transporting yarn, rovings or the like, said receptacle having one or more openings through its bottom, the bottom being shaped to discharge foreign matter by gravity through said opening or openings.

8. A portable receptacle for transporting yarn, rovings or the like, said receptacle having one or more openings through its bottom, said bottom being sloped downwardly at all points to said opening or openings at a sufficient angle to cause the loose foreign matter to be discharged by gravity therethrough.

9. A portable receptacle for transporting yarn, rovings or the like, and means for humidifying the contents of the receptacle, comprising a device for introducing the humidifying agent into the receptacle at the bottom thereof.

10. A portable receptacle for transporting yarn, rovings or the like, and means for humidifying the contents of the receptacle, comprising a device for introducing the humidifying agent into the receptacle at the top thereof.
11. A portable receptacle for transporting yarn, rovings or the like, and means for humidifying the contents of the receptacle, comprising a device for introducing the humidifying agent into the receptacle at the bottom and top thereof.
- In testimony, that we claim the foregoing as our invention, we have signed our names this 12th day of May 1922.

GEORGE S. BROWN.
LEWIS M. CARPENTER.
